UNITED STATES PATENT OFFICE.

THEODOR KUNDTZ, OF LAKEWOOD, OHIO.

DESIGN FOR A SEWING-MACHINE CABINET.

SPECIFICATION forming part of Design No. 35,732, dated February 11, 1902.

Application filed December 17, 1901. Serial No. 86,317. Term of patent 7 years.

To all whom it may concern:

Be it known that I, THEODOR KUNDTZ, a citizen of the United States of America, residing at Lakewood, in the county of Cuyahoga and State of Ohio, have invented and produced a new and original Design for Sewing-Machine Cabinets, of which the following is a specification, reference being had to the accompanying drawing, forming part thereof.

10 The figure is a view in perspective of a sewing-machine cabinet showing my new design, and this figure shows the forward side, the right-hand side, and the top of the cabinet.

15 My design for a sewing-machine cabinet comprises a horizontally-arranged top *a*. Two skeleton frames are arranged below and depend from opposite end portions, respectively, of the top *a* and comprise, respectively, horizontally-arranged shelves 5 and upright bars 6, connecting the said shelves with the top *a*, and drawers *c* are arranged upon the shelves. The front of each drawer *c* gradually recedes or extends inwardly, as at 7, toward the inner

25 side wall of the drawer, and at the said side has a molding 8, which extends vertically from top to bottom of the drawer. Each drawer *c* swells or curves outwardly, as at 9, at the junction of its front with the outer side

30 wall of the drawer, and a recess 10 is formed in the said side wall in close proximity to the said front, and ornamental work 12 is arranged at the forward side of the said recess. The forward edge of each shelf 5, forwardly of the

35 drawer upon it, conforms to the outline of the front of the said drawer. The drawers at the left-hand side of the cabinet, although only partially shown, are the same in design in every respect as the drawers at the right-hand

side of the cabinet. Another drawer *d* is arranged next below the forward portion of the top between the aforesaid skeleton frames and represents and forms a portion of the front of the cabinet. Opposite end portions 15 and 15 of the front of the drawer *d* are 40 straight, and the central portion 16 of the said front swells or curves forwardly, and moldings 17 are arranged upon the said front between the central portion 16 and the aforesaid end portions 15 and extend from top to 45 bottom of the said front. Ornamental scrolls 18 appear upon the faces of the straight end portions 15 of the front of the drawer *d*. The fronts of the drawers *c* and *d* form a cabinet-front which is comparatively plain and yet 50 handsome. The forward edge of the top *a* is provided with two inward curves 20 and 20 adjacent to opposite end portions, respectively, of the front of the drawer *d*. The curves 20 extend into the drawer-covering portions of the 55 top *a*. The forward edge of the top *a* swells or curves outwardly at the junction of its side edges with the forward edge.

The leading and characteristic and essential feature of my design comprises the unitary article in its aspect or shape or configuration as shown in the drawing.

What I claim is—

The design for a sewing-machine cabinet substantially as herein shown and described. 70

In testimony whereof I sign the foregoing specification, in the presence of two witnesses, this 14th day of December, 1901, at Cleveland, Ohio.

THEODOR KUNDTZ.
